UNITED STATES PATENT OFFICE.

FRANK E. HOUSH, OF BOSTON, MASSACHUSETTS.

DESIGN FOR AN ADVERTISING-CARD.

SPECIFICATION forming part of Design No. 34,121, dated February 19, 1901.

Application filed January 21, 1901. Serial No. 44,220. Term of patent 7 years.

To all whom it may concern:

Be it known that I, FRANK E. HOUSH, a citizen of the United States, residing at Boston, in the county of Suffolk and State of Massachusetts, have invented and produced a new and original Design for an Advertising-Card, of which the following is a specification, reference being had to the accompanying drawings, forming a part hereof, in which—

10 Figure 1 is a plan view of an advertising-card, showing my new design. Fig. 2 is a sectional view on line 2 2 of Fig. 1.

15 As shown in the drawings, the leading or material feature of my design consists in the advertising-card, rectangular in outline and provided with an oval space *a* and a square space *b*, substantially as shown in the drawings, the oval space being recessed or de-

pressed below the general surface of the card, while the square is elevated above the general surface of the card. This feature of elevation and depression of the two elements of my design is shown most distinctly in Fig. 2. Around and surrounding these oval and square spaces is the plane surface of the card *c*.

Having described my invention, what I claim as new, and desire to secure by Letters Patent, is—

20 The design for an advertising-card, as herein shown and described.

FRANK E. HOUSH.
